(57) **CLAIM**

The ornamental design for an electrical connector, as shown and described.

DESCRIPTION

FIG. 1 is a perspective view of an electrical connector having a connector body and a light;

FIG. 2 is a front view of the electrical connector in FIG. 1; FIG. 3 is a back view of the electrical connector in FIG. 1; FIG. 4 is a first side view of the electrical connector in FIG. 1;

FIG. 5 is a second side view of the electrical connector in FIG. 1;

FIG. 6 is a top view of the electrical connector in FIG. 1; FIG. 7 is a bottom view of the electrical connector in FIG. 1; and,

FIG. 8 is a perspective view of the electrical connector in FIG. 1, with the light removed from the claim.

The broken lines in the drawings illustrate portions of the electrical connector that form no part of the claimed design.

1 Claim, 5 Drawing Sheets
